UNITED STATES PATENT OFFICE.

OLIVER W. CHILDS, OF NASH, OKLAHOMA.

WIRE CLOTH OR SCREEN MACHINE.

1,077,040.

Specification of Letters Patent.

Patented Oct. 28, 1913.

Application filed May 18, 1912. Serial No. 698,140.

To all whom it may concern:

Be it known that I, OLIVER W. CHILDS, a citizen of the United States, and a resident of Nash, in the county of Grant, State of Oklahoma, have invented a new and useful improvement in Wire Cloth or Screen Machines, of which the following is a specification.

My invention is an improvement in wire cloth or screen machines, and has for its object the provision of a simple, inexpensive device of the character specified for holding a number of rolls of wire cloth of different size, each in a position easily accessible for inspection and sale, and wherein means is provided for registering the amount of cloth remaining after each sale, and wherein an indication of the said amount and quality is always visible.

In the drawings: Figure 1 is a front view of the improved device; Fig. 2 is an enlarged partial transverse section of the measuring device; Fig. 3 is a plan view of a portion of Fig. 2; Fig. 4 is an enlarged transverse section of the said measuring device; Fig. 5 is a perspective view of the measuring device; Fig. 6 is an enlarged detail sectional view of the receiving roller; Fig. 7 is a transverse vertical section of the indicator; Fig. 8 is a front view of the same; Fig. 9 is a perspective view of a holder with the parts separated; Fig. 10 is a section on the line 10—10 of Fig. 11; Fig. 11 is a section on the line 11—11 of Fig. 10; and Fig. 12 is a front view of the dial of a holder.

The present embodiment of the invention comprises a cabinet or casing of suitable size and with any desired ornamentation, and preferably composed of three sections, for convenience in shipping.

Each of the three sections 1 is the same, and all are supported on a suitable base 2. Each of the sections is provided with a plurality of separate compartments 3, nine in the present instance, and a holder 4, of trough shape, is held in each compartment. Each holder is provided with a lateral flange 5 at one of its side edges, and with a facing plate or front 4^a at its front end. A handle 6 is secured to each plate 4^a, and the said plate and handle extend outside of the cabinet. Each of the plates 4^a is provided with an opening 7 at its center, and each opening is closed by a sheet 8 of transparent material, as, for instance, glass. The opening is circular, and the edges of the plate 4^a extend

beyond the holder to form a stop for limiting the inward movement of the holder. A clip 9 is secured to the upper edge of each end of the holder, and the ends of a bar 10 are held beneath the clips. 60

The bar 10 has its ends rabbeted, as shown at 11, and the shoulder formed between the rabbeted portion and the main portion engages the inner face of the adjacent end to prevent longitudinal movement of the bar. 65 A roller 12 provided at its ends with journal pins 13 and 14 is arranged longitudinally of each holder, the pin 13 being journaled in an opening 15 in the rear end of the holder, and the pin 14 in a slot or recess 16 in the front end. The roller is also provided with an annular series of teeth 17 near its front end, and a pinion 18 is secured to the journal pin 14. The pinion meshes with a gear 70 wheel 19 on a shaft 20 journaled between the front end of the holder and a plate 21 arranged transversely of the holder near the said front end. The plate 21 is faced with metal on both faces, as indicated at 22, and 75 a similar facing 23 is arranged on the inner face of each end of the holder. 80

A block or filling 24 is arranged between the plate 21 and the front of the holder at one side, and a recess 25 is formed at the 85 other side for the indicating mechanism, of which the pinion 18, gear wheel 19 and shaft 20 are a part. A pinion 26 is secured to shaft 20 and meshes with a gear wheel 27 on a second shaft 28 journaled transversely 90 of recess 25 in the plate 21 and front of the holder. A pinion 29 on shaft 28 meshes with a gear wheel 30 on a shaft 31 journaled at the center of opening 7, and extending through the front end of the holder into a 95 recess 32 formed in the front face of the front end of the holder directly behind the opening 7. An indicating dial 33 is secured at the bottom of the said recess, and an indicator or hand 34 is secured to the front end 100 of shaft 31 in the said recess 32.

The indicator co-operates with the dial to indicate the operation of the roller 12, and the outer face of the dial is provided with an annular series of graduations 35, and with 105 an annular series of indicating numerals 36 inside the series of graduations. A separate measuring device is provided, and the said device is held in a casing 37, which may be arranged, as shown in Fig. 1, on one of the 110 sections of the cabinet. The said device is provided with a compartment or trough 38

at its rear for receiving the holders 4, and a cutting device is arranged at the front of the said compartment. The cutting device comprises a ledger blade 39 secured to the 5 front wall of the compartment, and a movable blade 40 coöperating with the ledger blade, and pivoted to the ledger blade at 41. The blade 40 is also provided with a handle 42 for operating the same, and the said 10 blades extend the full length of the compartment 38. The wire cloth 43 is placed in the trough in a roll, Fig. 4, and the free end thereof is passed over the roller 12. Whenever the free end of the cloth is drawn outwardly 15 the roller will be rotated and will operate the indicator 34.

A roller 44 is arranged in front of the ledger blade, the said roller having journal pins 45 which are secured in inclined slots 46 in the casing 37. A crank 47 is fitted on the outer end of one journal pin, which is made polygonal to receive the crank. The roller is provided with a longitudinal groove or recess 48 for receiving the free end of the 20 cloth, and clips 49 are secured to the roller in the recess for holding the said end. The said clips engage and hold the end of the cloth, and when the roller is turned by the crank 47 the cloth will be wound on the roller 25 and will be drawn from the holder, rotating at the same time roller 12. A substantially U-shaped bracket comprising a body 50 and arms 51, 51^a is arranged in front of the roller 44 and the body 50 is journaled in 30 bearings 52, on the frame or casing 37. A shaft 53 is journaled in the upper end of the arm 51^a, and a toothed wheel 54 is secured to one end of the shaft. A casing 55 is held at the upper end of arm 51, and the 35 other end of shaft 53 is journaled in the casing at the center thereof. The casing is composed of a ring having a transparent closure 56 at one end, and a dial 57 is held in the ring near the closure 56. The casing 40 is held in a ring or bearing sleeve 58 at the upper end of arm 51, and a handle 59 is provided at the top of ring 58. The dial 57 has a central opening, and a gear wheel 60 is provided with an arbor 61 for engaging 45 shaft 53, the said arbor extending through the opening of the dial and having an indicator or hand 62 between the dial and the closure. An indicator or hand 63 is secured to the shaft between the dial and the closure, 50 and the gear wheel 60 meshes with a pinion 64, rigid with a gear wheel 65 on a pin 66 extending rearwardly from the dial. The rear end of the pin is held in a bearing 67 on a three armed frame 68, having two of its 55 arms secured to the casing and having a bearing for shaft 53 at its center, and the gear wheel 65 meshes with a pinion 69 on the shaft.

The mechanism in casing 55 is operated 60 by the rotation of shaft 53 and is designed to

indicate on the dial the amount of cloth wound on roller 44. The cloth as it winds on the roller rotates wheel 54, which is swung over against the roll by handle 59. Two scales 70 and 71 are provided on dial 70 57, the hand 62 coöperating with scale 70 and hand 63 with scale 71.

The arm 51 is engaged by a spring 72 connected at one end to the arm, and at the other to an eye 73 in the casing 37, the 75 spring acting to hold the frame 50, 51, 51^a with the wheel 54 in engagement with the cloth. A spring clip 74 is secured to the casing for engaging arm 51 and holding the frame in the above position. 80

When it is desired to remove a predetermined amount of cloth from any holder, the particular holder is removed from the cabinet and placed in trough or compartment 38 of the measuring device. The free end of the cloth is drawn over roller 12, under bar 10, between blades 39—40, and is then connected to roller 44 by means of clip 49. The frame 50, 51, 51^a is swung rearwardly to bring wheel 54 into engagement with the cloth on the roller at the groove 48. The indicators 62 and 63 are at zero on the scales, and when the roller 44 is rotated by crank 47 the cloth is wound upon the roller 44, and the indicators 62 and 63 indicate the 85 amount wound on the dial 57. When the proper amount is indicated, the blade 40 is 90 operated to cut the cloth, and the roll of cloth may be slipped from roller 44. The roller 12 has meanwhile been operated to 95 operate the indicator 34, which indicates what amount of cloth remains in the holder. 100

A weight 75 Fig. 1, is provided for returning the indicator 62 and 63 to zero after the swinging frame has been swung forward to release the wheel 54 from the cloth. The said weight is connected to one end of a cord 76, whose other end is connected to the toothed wheel 54, at 77, and a turn of the cord is wound around the shaft 53. 110

The indicating mechanism at the end of each holder indicates the amount of cloth on the roll. The indicator is arranged to operate when the cloth is wound or unwound from the roll, and with no cloth on the roll 115 the indicator stands at zero, indicating the fact that there is no cloth on the roll. As the cloth winds on the roll the indicator commences to register and after the winding has been finished, the indicator will indicate 120 the amount of cloth on the roll. Say for instance, that there are 100 yards on the roll. Should now for instance 10 yards be drawn off and cut away, the indicator will be moved in the reverse direction to that which 125 it was moved when the cloth was being wound on the roll, and will indicate that there are but 90 yards now on the roll instead of 100 as before. During the winding of the cloth, the indicator or hand moves clock- 130

wise, while during the unwinding or the withdrawing of the cloth the indicator moves anti-clockwise.

I claim:

5. 1. A device of the character specified, comprising a cabinet having a plurality of compartments, a substantially trough shaped holder for wire cloth in each compartment, a roller journaled longitudinally of each holder and having an annular series of spurs or teeth for engagement by the cloth as it passes from the holder to rotate said roller, an indicating device at the front end of the holder, said device comprising a dial, the front end of the holder having an opening at the dial, an indicator coöperating with the dial, and a connection between the roller and the indicator for operating the same, a receptacle supported by the cabinet 70
15 for receiving the individual holders, a roller journaled in front of the receptacle and having means for gripping the end of the cloth, manual means for turning the roller, a fixed cutting blade at the front of the receptacle 20
25 over which the cloth passes, a movable blade pivoted at one end to the fixed blade, an indicating device, a shaft for operating said device, a toothed wheel on the shaft for engaging the cloth as it winds on the roller 25
30 to rotate the shaft, a frame mounted to swing toward and from the roller to bring the toothed wheel into or out of engagement with the cloth, a spring drawing said frame toward the roller, and means for locking the frame with the wheel in engagement 35
40 with the cloth.
2. A device of the character specified, comprising a cabinet having a plurality of compartments, a substantially trough shaped holder for wire cloth in each compartment, a roller journaled longitudinally of each holder and having an annular series of spurs or teeth for engagement by the cloth as it passes from the holder to rotate said roller, 45
45 an indicating device at the front end of the holder, said device comprising a dial, the front end of the holder having an opening at the dial, an indicator coöperating with the dial, and a connection between the roller 50
50 and the indicator for operating the same, a receptacle supported by the cabinet for receiving the individual holders, a roller journaled in front of the receptacle and having means for gripping the end of the cloth, manual means for turning the roller, an indicating device, a shaft for operating said device, a toothed wheel on the shaft for engaging the cloth as it winds on the roller 55
60 to rotate the shaft, a frame mounted to swing toward and from the roller to bring the toothed wheel into or out of engagement with the cloth, a spring drawing said frame toward the roller, and means for locking the frame with the wheel in engagement 65
70 with the cloth.
3. A device of the character specified, comprising a cabinet having a plurality of compartments, a substantially trough shaped holder for wire cloth in each compartment, a roller journaled longitudinally of each holder and having an annular series of spurs or teeth for engagement by the cloth as it passes from the holder to rotate said roller, 75
75 an indicating device at the front end of the holder, said device comprising a dial, the front end of the holder having an opening at the dial, an indicator coöperating with the dial, and a connection between the roller and the indicator for operating the same, a receptacle supported by the cabinet for receiving the individual holders, a roller journaled in front of the receptacle and having means for gripping the end of the cloth, manual means for turning the roller, an indicating device, a shaft for operating 80
85 said device, a toothed wheel on the shaft for engaging the cloth as it winds on the roller to rotate the shaft, a frame mounted to swing toward and from the roller to bring the toothed wheel into or out of engagement with the cloth, and means between the roller and the receptacle for cutting the cloth.
4. A device of the character specified, comprising a cabinet having a plurality of compartments, a substantially trough shaped holder for wire cloth in each compartment, a roller journaled longitudinally of each holder and having an annular series of spurs or teeth for engagement by the cloth as it passes from the holder to rotate said roller, 90
95 an indicating device at the front of the holder, and a connection between the roller and the said device for operating the same.
5. In a device of the character specified, a holder trough shaped in cross section and having a compartment at its front end, and a central opening in its front extending into the compartment, an indicating device in the said compartment, said device comprising a dial behind the opening and an indicator coöperating with the dial, a transparent cover for the opening, a roller journaled longitudinally of the holder and having an annular series of teeth for engagement by the cloth to rotate the roller, and a connection between the roller and the indicator for operating said indicator. 100
105
110
115
6. In a device of the character specified, a holder trough shaped in cross section and having a compartment at its front end, and a central opening in its front extending into the compartment, an indicating device in the said compartment, and visible through the opening, a roller journaled longitudinally of the holder and having teeth for engagement by the cloth to rotate the roller, and a connection between the roller and the indicating device for operating the said device. 120
125
7. A device of the character specified, 130

1 comprising a cabinet having a plurality of compartments, a trough shaped holder in each compartment for holding a roll of wire cloth, a toothed roller in each holder over which the cloth passes, an indicating device for each holder operated by the roller, for indicating the amount of cloth remaining in the holder, a receptacle on the cabinet for receiving the individual holders, a roller 10 having means for engaging the end of the

cloth, means for turning the roller to wind the cloth thereon, and means movable toward and from the roller for measuring the cloth winding on the roller, said means being operated by the movement of the cloth. 15
